US00D584345S

(12) **United States Design Patent**
Choi et al.

(10) **Patent No.:** US D584,345 S
(45) **Date of Patent:** ** Jan. 6, 2009

(54) **DEVELOPING DEVICE FOR LASER
PRINTER**

(75) Inventors: **Jai-Il Choi**, Kyunggi-do (KR);
Sang-Hun Lee, Kyunggi-do (KR)

(73) Assignee: **Samsung Electronics Co., Ltd.**, Suwon,
Kyunggi-Do (KR)

(**) Term: **14 Years**

(21) Appl. No.: **29/294,095**

(22) Filed: **Dec. 21, 2007**

(51) **LOC (9) Cl.** 16-03

(52) **U.S. Cl.** D18/43

(57) **CLAIM**

The ornamental design for a developing device for laser
printer, as shown and described.

DESCRIPTION

FIG. 1 is a top front perspective view of a developing device
for laser printer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict environmental subject matter only
and form no part of the claimed design.
